G. S. GREENE.

MINE CAR BUMPER.

APPLICATION FILED JUNE 26, 1912.

1,066,603.

Patented July 8, 1913.

UNITED STATES PATENT OFFICE.

GEORGE S. GREENE, OF ST. CLAIRSVILLE, OHIO.

MINE-CAR BUMPER.

1,066,603.

Specification of Letters Patent.

Patented July 8, 1913.

Application filed June 25, 1912. Serial No. 705,891.

To all whom it may concern:

Be it known that I, GEORGE S. GREENE, a citizen of the United States, residing at St. Clairsville, in the county of Belmont 5 and State of Ohio, have invented certain new and useful Improvements in Mine-Car Bumpers, of which the following is a specification.

This invention relates to mine cars, and 10 particularly to the bumpers and draw-bars thereof.

The object of the invention is to provide such cars with an improved form of bumper, which will avoid the mutilation or breakage 15 of the coupling link or of the parts of the draw head, and which can be repaired or renewed at a low cost and in a convenient manner.

The ordinary type of draw-bar is objectionable and gives considerable trouble by reason of breakage of the draw-bar or link when the cars come together with a shock.

By means of my improvement the draw head is protected, and a space is provided 25 so that the link will not receive the impact of cars bumping together.

The invention can be easily applied to the ordinary type of mine car without particular modification thereof. It comprises a 30 new form and construction of the bumper head as will more fully appear from the following description and the accompanying drawings.

In the drawings, Figure 1 is a plan view 35 of the bumper. Fig. 2 is a side elevation. Fig. 3 is a section on the line 3—3 of Fig. 2.

Referring specifically to the drawings, 6 indicates the main or middle sill of the car which is extended beyond the end thereof 40 as usual, and 7 is the metal draw bar or plate which extends throughout the length of the car, and is suitably fastened to the middle beam or floor, and terminates short of the end thereof, as shown.

45 The end of the sill is provided with a metal binder 8 which is bent or fitted around the sides and front of the sill, as shown in Fig. 1 and this binder is fastened to the sill by transverse bolts 9 extending through the 50 sill. This protects the end of the sill and forms the bumper which contacts with the similar bumper of an adjacent car when the cars come together.

The upper surface of the sill, at the end 55 thereof, is provided with a top plate 10, and

the lower surface is provided with a bottom plate 11, these plates being made of metal, and being the same shape, in plan, as the end of the sill, and they are set in recesses made in the sill so that they are flush 60 with the top and bottom surfaces of the sill respectively and with the edges of the binder 8. They serve to support the binder and to strengthen the sill, and the upper plate forms a surface on which the link rests 65 when the cars are coupled. These top and bottom plates are secured to the sill by countersunk bolts 12.

An arched draw plate 13 is mounted on top of the sill, the edges of said plate being 70 angular and bent or set down to form flanges 14 at opposite sides, these flanges resting on top of the sill where they are secured by vertical bolts 15 extending through the sill. The plate forms an arched passage or recess 75 16 thereunder, of sufficient height to permit a link to pass back into the recess and under the plate, so that the link will not be jammed against the draw head, as in the old construction. The front end 80 of the draw plate 13 does not extend out as far as the end of the sill 6, and consequently cannot receive the bumping impact of cars. Said end is provided with a hole 17, in line with the hole 18 in the sill, to receive 85 the ordinary coupling pin. The rear end of the arched plate 13 is bent down as indicated at 19 and is attached by bolts 20 to the draw plate 7 and the sill 6.

The pulling strain on the car is thus 90 mainly communicated through the plate 13 to the draw-bar 7 and the middle sill.

When the coupling link enters the space between the front end of the draw plate 13 and the plate 10 it may pass or work back 95 into the recess 16, and so be relieved of any impact incident to operation of the ears. In the event of breakage of any of the metal parts they can be easily replaced. This is 100 particularly advantageous with respect to the draw plate 13, which some times breaks. To replace it, it is only necessary to take off the old plate by removing the bolts 15 and 20, and put a new one on, and this can be done without renewing the other parts of the bumper head, and is superior to the old form in which the draw plate was integral with the bumper or was welded to the draw-bar 7, requiring either a new bumper head 105 or the welding of a new draw plate to the 110

end of the draw-bar, as well as putting the car out of use for a considerable period of time.

I claim:

5 The combination with a sill provided at its end with a top plate, and a draw-bar mounted on top of the sill, of a draw plate having a hole for the coupling pin, said draw plate being arched transversely to the
10 sill and bolted at its side edges to the sill,

and bolted at its rear end to the draw-bar, whereby the draw plate may be removed without removal of the top plate or the draw-bar.

In testimony whereof, I affix my signature 15 in presence of two witnesses.

GEORGE S. GREENE.

Witnesses:

S. E. LEWIS,
S. M. GELLER.
